ANDREW WAGNER, OF WEST HOBOKEN, NEW JERSEY, ASSIGNOR TO FERGUSON BROTHERS MANUFACTURING COMPANY, OF HOBOKEN, NEW JERSEY, A CORPORATION OF NEW JERSEY

FOLDING TABLE

Application filed March 3, 1928. Serial No. 258,816.

This invention relates to folding tables and more particularly to the folding leg structure adapted for use on portable tables, such as card tables, and it comprises improved means for latching the table legs when in use.

An object of the invention is to provide a structure which is strong, rigid, durable and not encumbered by brace rods and guide ways.

A further object of the invention is to provide a simple and efficient means of mounting and holding the legs in position within the table top.

A still further object of the invention is to provide certain improvements in the form, construction and arrangement of the several parts whereby the above named and other objects may be effectively attained.

A practical embodiment of my invention is represented in the accompanying drawings, in which

Fig. 1 represents a detail inverted plan view, partly in section, of a portion of a table having applied thereto my improved folding leg structure in its folded position in the table;

Fig. 2 represents a detail vertical section, on a larger scale, taken in the plane of the line II—II of Fig. 1, looking in the direction of the arrows, and

Fig. 3 represents a similar view with the leg in position as in use.

In the drawings I have shown my improved folding leg applied to an octagonal table and, in Fig. 1 I have represented a portion of two legs in the position they will assume in the table when folded.

The side frames of the table are denoted by 1, the top by 2 and the covering for the top by 3. The frame, top and cover are assembled in any well known or approved manner. A chip rack 4 is secured to each of the side frames 1 in the usual manner.

Each folding leg structure comprises a leg 5 having its upper end 6 pivoted to swing on a bolt 7, one end of which is mounted in a cheek piece 8 secured by screws 9 to a filler block 10 fixed in the angle of two adjacent side frames, while the other end of the bolt 7 is supported

in a bracket 11 fastened to the side frames 1 and block 10 by screws 12. The head 13 of the bolt is square and is housed in a square hole 14 in the filler block 10, to prevent the bolt from turning when the leg is swung thereon. The opposite end of the bolt 7 is screw threaded to receive a thumb screw 15, which is manipulated to increase or decrease the frictional contact between the end of the leg 6, cheek piece 8 and the bracket 11.

The upper end 6 of the leg 5 is notched at 16 and the arrangement of the bolt therein is such as to allow the leg to lie flat against the under surface of the top 2 when folded, as clearly shown in Fig. 2, while the notched portion 16 is arranged to engage the filler block 10 when the leg is in use, as shown in Fig. 3.

A latch 17 is disposed in a longitudinal slot 18 in the upper end of the leg 5 and secured therein by means of a screw 19 passing through a hole 20 in the end of the latch. A spring 21 is seated in a recess 22 formed in the bottom of the slot 18 and arranged to exert pressure against the latch 17 to force it outwardly. The outward movement of the latch is limited by the head 23 of the screw 24, which passes through a hole 25 in the latch and is secured in the bottom of the recess 22. The bottom of the longitudinal slot 18 is inclined so that the free end of the latch 17 may swing inward therein. This free end of the latch is provided with a hook having a rounded end 26 terminating in an outward and downward portion 27.

This hooked end of the latch is arranged to be brought into engagement with a keeper 28 secured to the side frame 1 by screws 29. The keeper 28 has a hole 30, one edge of which is disposed in position to be engaged by the rounded end 26 and the outward and downward portion 27 of the hook, which engagement forces the latch, against the tension of the spring 21, until the portion 27 passes into a recess 31 in the filler block 10, whereupon the spring will exert its tension and the hook and latch become interlocked with the keeper 28 as clearly shown in Fig. 3.

In this position it will be seen that the notch is held firmly against the filler block

10, thereby forming a solid support for the leg.

For convenience, the latch is provided with a button 32, which is manipulated to move the 5 latch and release the hook from the keeper 28.

When it is desired to fold the leg 5 against the table top, the button 32 is pressed so that the latch 17 will rock on its screw 19 and re-cede into the longitudinal slot 18 against the 10 tension of the spring 21, as shown in dotted outline in Fig. 3. This movement of the latch places the portion 27 of the hook in position to be removed from the hole 30 in the keeper 28 by swinging the leg on its 15 pivot 7. The leg 5 is held in its folded position by frictional contact of the upper portion 6, cheek piece 8 and bracket 11.

It is obvious that various changes may be resorted to in the form, construction and arrangement of the several parts without departing from the spirit and scope of my invention; and hence, I do not intend to be limited to the details herein shown and described, except as they may be included in the 25 claims.

What I claim is:

1. A folding table comprising, a top including a depending frame, foldable legs, means for pivoting the legs to said frame, 30 each of said legs having a notch adjacent its pivoted end arranged to engage the frame when in its unfolded position, keepers on the frame, each of said legs also having a longitudinal recess opening into said notch, a 35 spring actuated latch pivoted in each recess and provided with a hooked end disposed in position to overhang the notch and project outwardly from the recess, said legs being arranged to be swung to bring said hooked 40 ends into coaction with the keepers for automatically locking the legs in their unfolded position.

2. A folding table comprising, a top including a depending frame, foldable legs, 45 means for pivoting the legs to said frame, each of said legs having a notch adjacent its pivoted end arranged to engage the frame when in its unfolded position, keepers on the frame, each of said legs also having a longitudinal recess opening into said notch, a 50 spring actuated latch pivoted in each recess and provided with a hooked end disposed in position to overhang the notch and project outwardly from the recess, said legs being 55 arranged to be swung to bring said hooked ends into coaction with the keepers for automatically locking the legs in their unfolded position, said latches being manually operated to release the hooked ends from the 60 keepers and the legs from their locked position.

In testimony that I claim the foregoing as my invention, I have signed my name this 1st day of March, 1928.
